UNITED STATES PATENT OFFICE.

PETER F. WHITE AND MERCER M. LEONARD, OF LEAVENWORTH, KANSAS, ASSIGNEES
OF ONE-FIFTH TO WILLIAM KUBINA, OF CHARLEROI, PENNSYLVANIA.

TWIN VACUUM-TURBINE.

1,112,956.

Specification of Letters Patent.

Patented Oct. 6, 1914.

Application filed April 28, 1914. Serial No. 834,997.

To all whom it may concern:

Be it known that we, PETER F. WHITE and MERCER M. LEONARD, citizens of the United States, residing at Leavenworth, in the county of Leavenworth and State of Kansas, have invented certain new and useful Improvements in Twin Vacuum-Turbines, of which the following is a specification.

This invention relates to twin vacuum turbines, designed for the purpose of producing energy or power without requiring an exhaust into the atmosphere.

Another object of the invention is to provide a twin vacuum turbine to be run by two separate and distinct gases which when they unite after having expended their power in rotating the turbine are converted into a liquid which can be run off at will, thus providing a turbine which can be used in submarine boats or in other positions where an exhaust into the atmosphere would be impossible.

Still another object of the invention is to provide a turbine to be run by two comparatively inexpensive gases and which will develop considerable power at slight expense, and in which the exhaust of the two gases would be converted into a liquid which could be readily run off and disposed of under conditions which would not be possible with a steam or other form of turbine requiring an exhaust into the atmosphere.

These and other objects may be attained by means of the construction illustrated in the accompanying drawings, in which,

Figure 1 is a side elevation of a twin turbine made in accordance with this invention, Fig. 2 is a vertical sectional view through one of the cylinders and its valve mechanism and the turbine wheel, Fig. 3 is an end elevation of the twin vacuum turbine, and Fig. 4 is a vertical section taken longitudinally of the casing.

Referring to the drawings, the numeral 1 designates a double cylinder mounted on a hollow base 2, and extending into said cylinder is a shaft 3 to which is keyed a hub 4 of the turbine wheel, said wheel being provided with radial blades or vanes 5, and said shaft being mounted on ball bearings 6. The cylinder 1 is divided by a central partition 7.

Mounted on the cylinder are two separate and distinct valve casings 8 and 9, one upon each side of the partition 7. Extending through the valve casings 8 and 9 is a shaft

10, and mounted on said shaft are valves 11 and 12, said valves being of identical construction, and each valve comprising a disk having an opening extending through the same from periphery to periphery, and an acetylene gas pipe 13 communicates with the valve casing 8 and a hydrogen-chlorin gas pipe 14 communicates with the valve casing 9. The intake duct 15 in the valve 8 is provided with oppositely disposed branch ducts 65 a—b, and at opposite sides of the valve 11 these ducts are continued to form branches c—d.

A handle or lever 16 is connected to the shaft 10 for operating the valve, and it will be readily apparent that a movement of the handle 16 will operate both the valve 11 and 12 simultaneously to open communication from the pipes 13 and 14 to the cylinder through the ducts c and d, and the gases 75 which impinge upon the vanes 5 push the turbine wheel in one direction or the other dependent upon the movement of the handle 16. The acetylene gas and the hydrogen-chlorin gas are kept separated until they 80 have performed their function of rotating the turbine wheel and when they are discharged at the lower end of the wheel, the gases unite and form a liquid which drops into the reducing chamber e having an outlet f.

Acetylene gas can be produced by use of calcium carbide and water, and hydrogen-chlorin gas can be generated in the same kind of generator by the use of sulfuric acid 90 and salt. These two gases are comparatively inexpensive to manufacture and they are both capable of developing considerable power. The great advantage of their use in the present instance, is that the exhaust 95 from the use of these gases forms a liquid which can be run off and disposed of without access to the outer atmosphere and thus rendering the invention particularly desirable for submarine purposes.

Various changes may be made in the details of construction of the turbine without departing from the spirit and scope of the invention as defined in the claims.

What is claimed is:

1. A double turbine wheel comprising a cylinder having two compartments therein, a wheel mounted upon a single shaft and mounted in said compartments, gas feed pipes leading into each compartment, valves 105 110

for controlling the flow of gas in said compartments and a reducing chamber underneath the turbine wheels whereby said turbine wheel may be operated by two separate and distinct gases which unite after their force has been spent to form a liquid, thus obviating the necessity of an exhaust into the atmosphere.

2. A turbine wheel comprising a cylinder having a partition therein, a turbine wheel mounted in each chamber at opposite sides of the partition, and means for leading two separate and distinct gases into said chambers, said gases adapted to unite after they have expended their force and form a liquid, thus obviating the necessity of an atmospheric exhaust.

3. A method of rotating turbine wheels which consists in leading acetylene gas and hydrogen-chloride gas into separate chambers to utilize combined forces, and permitting said gases to exhaust and unite to form a liquid.

4. A twin motor or turbine wheel comprising a casing, a partition in said casing, a rotor mounted in each of said chambers in opposite sides of the partition, means for controlling two separate gases for admission

into said chambers, and a reducing chamber underneath the rotor to receive the said gases in the form of a liquid.

5. A double turbine comprising a casing having separate and distinct chambers, turbine wheels mounted upon a single shaft and disposed in said chambers, means for controlling two separate and distinct gases, one for each chamber, and a reducing chamber underneath the turbine wheels to receive the exhaust of the gases in the form of a liquid.

6. A double turbine adapted to be operated by acetylene gas and hydrogen-chloride gas, and comprising two cylinder chambers, turbine wheels mounted in said chambers, means for admitting the separate gases in each separate chamber, and a reducing chamber underneath the turbine wheels to receive the exhaust gases in the form of a liquid.

In testimony whereof we affix our signatures in presence of two witnesses.

PETER F. WHITE.
MERCER M. LEONARD.
